CLAIM

The ornamental design for a gull wing truck box, as shown and described.

DESCRIPTION

FIG. 1 is a gull wing truck box in a top perspective view; FIG. 2 is a bottom perspective view thereof; FIG. 3 is a front view thereof; FIG. 4 is a rear view thereof; FIG. 5 is a left side view thereof; FIG. 6 is a right side view thereof; FIG. 7 is a top view thereof; and, FIG. 8 is a bottom view thereof.

In the drawings, the broken lines depict unclaimed portions of the design only and form no part of the claimed design.
